UNITED STATES PATENT OFFICE.

CHARLES D. BONSALL, OF PARNASSUS, PENNSYLVANIA, ASSIGNOR TO WALTER P. MURPHY, OF NEW YORK, N. Y.

CAR-WALL STRUCTURE.

Application filed October 6, 1919. Serial No. 328,853.

To all whom it may concern:

Be it known that I, CHARLES D. BONSALL, a citizen of the United States, residing at Parnassus, in the county of Westmoreland 5 and State of Pennsylvania, have invented certain new and useful Improvements in Car-Wall Structures, of which the following is a specification.

My invention relates to the construction 10 of railway cars, particularly box cars, and the principal object of the invention is to provide a reinforced sheet metal wall structure for a railway car, particularly for the end of the car, which will be made up of a 15 relatively large number of corrugated, ribbed or embossed sections which are relatively narrow and have a configuration which makes it possible to press the sections on smaller, lighter presses than are commonly used for pressing the type of corrugated steel end plates commonly used at 20 the present time.

A further object is to provide an end 25 structure for a railway car which will be very strong and light and at the same time inexpensive to manufacture.

A further object of the invention is to 30 provide a ribbed or corrugated car wall comprising a plurality of sections, overlapped at their meeting edges, in which the corrugations are so disposed that the aggregate areas of metal on opposite sides of a 35 plane midway between the crests of the corrugations and hollows between the same are substantially equal so as to give the structure maximum strength in proportion to the weight of metal employed.

The invention is illustrated in the accompanying drawings wherein—

40 Fig. 1 is an end view, in elevation, of the superstructure of a railway car provided with an end wall constructed in accordance with my invention.

Fig. 2 is a sectional plan on line 2—2 45 of Fig. 1.

Fig. 3 is a side elevation of the end of the car.

Fig. 4 is a vertical section on line 4—4 50 of Fig. 1.

Fig. 5 is a fragmentary plan view of the end of the car with the roof boards removed.

Fig. 6 is a view, in perspective, of a portion of one of the intermediate end sheets.

Fig. 7 is a view similar to Fig. 4, illustrating a modified construction in which maximum strength is obtained for a given weight of metal, as mentioned above, and

Fig. 8 is a diagram to illustrate more fully the principle of construction of the 60 wall structure shown in Fig. 7.

Like characters of reference designate like parts in the several figures of the drawings.

Referring first to Figs. 1 to 6 inclusive, 65 which shows the invention as applied to the construction of a corrugated or ribbed steel end wall for a single sheath box car of common construction (it being understood that the invention is not limited to this particular type of car), 10 designates the side sheathing of the car, 11 the side plates, 12 the center sills, 13 the side sills, 14 the end sill, 15 the striking casting, and 16 the ridge pole of the roof. The end 70 wall is made up preferably of a corrugated or ribbed steel structure provided with a wooden lining. The steel end structure is made up of a plurality of relatively narrow, horizontally disposed sections. (al- 75 though the sections might run vertically) which have their meeting edges overlapped and offset or pressed out to provide hollow ribs or corrugations. The structure is pref- 80 erably composed of an upper section of sheet 17, a lower section 18, and a plu- 85 rality of intermediate sections 19. The lower edge 20 of section 18 is riveted to the end sill angle 14. A short angle bar 21 intervenes between the outer face of the 90 sheet and the striking casting 15. The up- 95 per edge of the upper section 17 is prefer- 100 ably bent over on diagonal lines to conform to the slope of the roof and provide inturned flanges 22, taking the place of the ordinary end plate, which are fastened at their ex- 105 tremities by gusset plates 23 to the side plates 11. An angle plate 24 on the inside of sec- 110 tion 17 supports the ridge pole and also the purlins (not shown). The upper edge 25 of the lower sheet 18, the lower edge 26 of the upper sheet 17 and the upper edges 27 and lower edges 28 of the intermediate sheets are formed with offsets, as indicated at 29, (Fig. 6) so that hollow ribs or cor- 115 rugations are formed at the seams or meet- 120 ing edges of the sheets which, preferably, terminate within the lateral edges of the

- sheets. These lateral edges are bent at right angles to the body of the sheet to provide flanges 30 for attachment to the side wall of the car. The overlapping meeting edges of the sheets are secured together, for example, by rivets 31. The sheets are also preferably formed with one or more corrugations or embossments 32 which are pressed out at the center portion of each sheet and have preferably flat tops with flat sloping sides and ends as shown. The sections so formed may be easily pressed on presses of comparatively light weight. The stretch of the metal is minimized since there is but a single corrugation pressed in each sheet so that the danger of rupture of the plates in pressing is minimized. If desired the corrugations 32 might be omitted which would still further facilitate the pressing of the sheets. If desired the end structure, as above described, might be anchored to the framing of the car by diagonal tie rods 33 and gussets 34, as well as by the flanges 30. The lining consists preferably of vertical lining boards 35 which are fastened to cleats 36 arranged in the corrugations 32. At the top of the lining boards is a cross timber 37 in the nature of a finishing strip.
- In Figs. 7 and 8 I have shown the arrangements, referred to in another part of the specification, for making the disposition of the area of metal equal on opposite sides of a vertical plane lying midway between the crests and hollows of the corrugations. In this construction the end comprises a plurality of sections which are all alike except the upper section and lower sections, the intermediate sections being designated 38, the upper section 39 and lower section 40. The upper section is provided with flanges 41 constituting the end plate of the car. Each section is shown as provided with two corrugations 42. The number, however, is immaterial. The intermediate sections are alternately inverted, one with respect to the other. As a result the overlapped edges of the sections are sometimes at the crests of the corrugations, as indicated at 43, and in others at the hollows between corrugations, as indicated at 44. This is a desirable construction but it is not essential to the principle, to be explained, whereby the maximum strength is obtained for a given weight of metal. This feature depends upon making the corrugations formed at the lapping of the sheets or the hollows between corrugations formed at the lapping of the sheets narrower than the other corrugations or hollows to the extent of the overlap, the other corrugations and hollows being of equal width, that is, the distances between their center lines being equal.
- Referring to Fig. 8, $u-u$ represent a plane midway between the crests of the corrugations and the hollows between corrugations. Considering the structure as a vertically placed beam, $u-u$ represent the geometrical axis of the beam. $v-v$ and $w-w$ are center lines of the hollows between one of the corrugations 43 formed at a seam between the end wall sections. $x-x$ and $y-y$ are center lines of corrugations 32 on opposite sides of one of the overlaps 44. $z-z$ is the center line of the corrugation on the other side of the corrugation through which line $y-y$ passes. If the width of the overlap be represented by A and the distance between line $y-y$ and $z-z$ by B, then the distance between lines $v-v$ and $w-w$ and between lines $x-x$ and $y-y$ should be B minus A.
- It will be understood that this principle of construction is also applicable to a sheet metal wall structure in which the corrugations extend in both directions from the plane of the margins of the sheets. In such case the terms "corrugations" and "hollows between corrugations" would be purely relative terms.
- I claim:
1. The combination with the end framing of a railway car, of a sheet metal wall structure for the end of the car comprising a plurality of sheets having horizontal meeting edges overlapped, and flanged on their vertical edges for attachment to the car framing, said overlapped edges being offset to form hollow strengthening ribs which merge into the sheets within said flanges, said sheets being also formed with pressed ribs between said overlapping edges. 90
  2. The combination with the end framing of a railway car, of a sheet metal wall structure for the end of the car comprising a plurality of sheets having horizontal meeting edges overlapped, and flanged on their vertical edges for attachment to the car framing, said overlapped edges being offset to form hollow strengthening ribs which merge into the sheets within said flanges, said sheets being also formed with pressed ribs between said overlapping edges. 95
  3. A sheet metal wall structure for a railway car comprising a plurality of overlapping sheets having corrugations pressed therein and having their overlapping margins offset to form ribs similar to, but of less width than said corrugations, whereby the amount of metal in a rib is substantially equal to that in a corrugation. 100
  4. A sheet metal wall structure for a railway car comprising a plurality of overlapping sheets having horizontal, parallel ribs pressed therein, and terminating within the sides of the sheet, said sheets having their overlapping margins offset to form ribs having the same amount of metal therein as the first named ribs whereby in the corrugated portion of the sheet 115

tially the same amount of metal on both sides of a plane parallel to the wall passing midway through said ribs.

5. A sheet metal end wall for a railway car comprising a plurality of sheets having one edge, in each case, offset and the opposite edge in the plane of the body of the sheet, the sheets being arranged with the offset edge of one sheet overlapped and joined to the offset edge of another sheet so as to form strengthening ribs at each alternate joint between the sheets.

6. A sheet metal end wall for a railway car comprising a plurality of sheets having one edge, in each case, offset and the opposite edge in the plane of the body of the sheet, the sheets being arranged with the offset edge of one sheet overlapped and joined to the offset edge of another sheet so as to form strengthening ribs at each alternate joint between the sheets, said sheets being also formed with ribs pressed from the sheet between their edges and parallel to the aforesaid ribs.

25 7. A sheet metal wall for a railway car comprising a plurality of sheets having their adjacent edges offset from the body of the sheet, the sheets being arranged with the offset edge of one sheet overlapped and joined to the offset edge of another sheet, said sheets being formed with a pressed rib between said overlapping edges, a nailing

strip positioned within said rib, and a lining in contact with said nailing strip.

8. A sheet metal wall for a railway car 35 comprising a plurality of sheets having their adjacent edges offset from the body of the sheet, the sheets being arranged with the offset edge of one sheet overlapped and joined to the offset edge of another sheet, 40 said sheets being formed with a pressed rib between said overlapping edges, a nailing strip positioned within said rib, and a lining in contact with the body of said sheets and said nailing strip. 45

9. A sheet metal end wall for a railway car comprising a pair of sheets having their adjacent edges flanged, said flanges being reflanged, said reflanged portions overlapped and secured together, said flanges decreasing in height toward the side of the car, whereby the overlapping of said sheets is increased in width. 50

10. A metallic wall for railway cars comprising a plurality of plates having integral corrugations formed therein, each corrugation having a substantially flat crest, said plates overlapped and secured together, the area of the overlapped portions of said plates being substantially equal to the area 55 of said crest, whereby the neutral axis is retained near the geometrical axis of said wall. 60

CHARLES D. BONSALL.
